Patented Mar. 13, 1917.

UNITED STATES PATENT OFFICE.

HENRY SYMES, OF MORNINGTON, NEAR DUNEDIN, NEW ZEALAND.

AUTOMATIC RECORDING FIRE-ALARM.

1,219,189.

Specification of Letters Patent.

Patented Mar. 13, 1917.

Application filed October 8, 1913. Serial No. 794,178.

To all whom it may concern:

Be it known that I, HENRY SYMES, tramways manager, town clerk, a subject of His Majesty the King of Great Britain, residing 5 at Mornington, near the city of Dunedin, in the British Dominion of New Zealand, have invented certain new and useful Improvements in Automatic Recording Fire-Alarms; and I do hereby declare the following to be 10 a full, clear, and exact description of the invention, such as will enable others skilled in the art to which it appertains to make and use the same.

The object of this invention is to set forth 15 a means of, and suitable apparatus for, forwarding signals, or otherwise giving alarms, such as of fire, or the like.

Also when needed, of recording the exact 20 situation from which such signal was given. For this purpose I employ electrical currents, and when signals are given from a considerable distance, they are preferably received by the usual type of drop shutter, which automatically closes a local circuit 25 strong enough for actuating the various apparatus needed for the purpose. Referring to the accompanying drawing,

Figure 1 represents a diagrammatic view 30 showing parts in section and elevation and embodying the features of the invention.

Fig. 2 is a diagrammatic plan view showing a modification of a part of the structure.

Figs. 3 and 4 are respectively an end and 35 side elevation showing a circuit closing mechanism embodied in the modification shown by Fig. 2.

A¹ A¹, are wires from a street alarm box B⁴, as shown by Fig. 1, or from a building B⁵, as shown by Fig. 2. A² A² are wires for 40 house protection in the modification shown by Fig. 2. Signals from wires A¹, whether by pressing a button or from the closing of a circuit formed by wires A², are received by the usual drop shutter A⁴, the latter releasing the circuit closer A⁵ which drops into the mercury cups A⁶ by the actuation of an electro-magnet B to which the said wires A¹ are connected, thus closing a local circuit A⁷ 45 including a battery B⁶. This causes the magnet B to attract the armature C, which releases the bell-crank D and allows the hooked arm E, and consequently the water-tank E¹ to slide down the tube F to the lower position (dotted). This sliding movement of the tank actuates a signal, such as 50 a whistle E⁸ by pulling a cord C⁴ connected

to the upper portion of the tank E¹ and running upwardly over a sheave S³ and connected to a frame E⁵ which in turn is attached by a continuation of the same cord to the operating means for the whistle E⁸. A spring E⁴ is also attached to the frame E⁵ which operates to restore the frame and the parts connected thereto to normal position when released, the frame E⁵ carrying a pawl E⁶ coöperating with an incline E⁷ at the end of a projection or arm E⁸, the pawl E⁶ being adapted to engage a catch H. The tube F has longitudinal slots F¹ and F² which provide overflow means for the tank E¹ into 60 the said pipe F in accordance with the elevated and lowered positions of the said tank.

In the lower position, tank E¹ empties automatically through the slots F¹ and the 65 block E² on arm E, which forms a part of a locking mechanism, is retained under spring catch G, holding tank E¹ down, for if not held, it would rise while emptying. The float L lowers with it and continues to lower 70 till the tank is empty when a circuit closer L¹ connected to the float L engages the mercury cups L² and closes the electrical circuit A⁷ including the said cups as shown by Fig. 1 which attracts the armature C to remove 75 catch G from block E² by the bell-crank-arm C¹.

The lightened tank now rises and as the spring D¹ lifts back bell-crank D, the tank is automatically reset in its operative position. This lifting is effected by spring E⁴ which latter pulls frame E⁵ with it, whereby pawl E⁶, which is at that time engaged with catch H, pulls said catch in the same direction, thus opening valve H¹ in the siphon 90 pipe and thereby starting the operation of the siphon. The catch H is held in this position by means of a spring-pressed latch J, which is connected with the usual float lever for controlling the passage of the water 95 from the main M, said catch being released when the float lever sinks and pulls latch J downward with it, whereupon valve H¹ closes and the water that remains siphons into the tank E¹. The upper tank, from 100 which the siphon pipe leads, is then refilled from the mains at M, in the usual way, both tanks being of the proper size to fill from the upper to the lower as described. The lifting of tank E¹ lifts the circuit closer L¹ 105 and opens the circuit A⁷, thus the apparatus and opens the circuit A⁷, thus the apparatus is ready for another signal. The fixed arm

E by resting on the point of the bell-crank lever D holds the tank up. When the electro-magnet B² attracts the armature C the free end of the said armature is then raised clear 5 of the short or top arm of the bell-crank D, thus releasing the said bell-crank from engagement with the fixed arm E and permitting the tank to drop or fall to the position shown in dotted lines, the block E² of the 10 said arm E engaging under the point of the spring catch D¹ which retains the tank in lowered position when empty, the spring E⁴ operating at the proper interval to restore the tank to its normal elevated position. 15 When the electrical bridge L¹ is lowered and closes the circuit through the cups L² the armature C is again attracted by the electro-magnet B and the spring catch is retracted from the block E², thus permitting the tank 20 E to rise. The bell-crank D is pivoted as shown and only has a slight movement, or a movement sufficient to permit the end of the arm E adjacent thereto to pass downwardly or clear the same. The arm E 25 always moves with the tank as it is fixed to the latter, and when the said arm is released from the catch G the long or horizontal arm of the bell-crank D is raised by the spring D¹ connected to the lower side of the arm E and adapted to engage under the longer arm of the said bell-crank D. Consequently, when the arm E rises with the tank the bell-crank D is restored to normal position for engagement by the free end of the armature C through the medium of the spring 30 D¹. The catch H slides horizontally, being pulled by the pawl or member E⁶, the said latter member or pawl rising as it pulls. The engagement of the catch H by the pawl 35 or member E⁶ continues and the drawing action on the said catch ensues until the locking catch J engages the recess in the under side of the catch H as shown, the locking catch thus holding the catch H until the 40 float and lever connected to the cut-off valve of the inlet pipe M descend, the said float and lever being attached to the locking catch J and by their descent exert a downward pull on said catch which results in a release 45 of the catch H, and the valve H¹ which is connected to the latter catch is thereby permitted to quickly drop and close the air vent of the siphon S¹, but the float tank is relieved of its contents by flow thereof 50 through the main body of the said siphon into the tank E¹. It will be understood that the tank in which the float and arm for the cut-off valve of the inlet pipe M are located will be controlled as to the quantity of water 55 running therein through the buoyancy of the float, which acting through the lever arm will either open or close the valve in accordance with the level of water in the tank. This is a well known structure and is common 60 in all flushing tanks.

When the tank E¹ is lowered, it automatically resets the drop shutter A⁴ owing to its cord connection with the weight K, thus drawing the circuit closer A⁵ to the position shown. When tank E¹ is at the low point, 70 signals from the clockwork gear O which revolves a signaling disk O¹ are transmitted to signaling mechanism herein described. The tank E¹ and the tank from which the siphon projects will have approximately the same capacity, that is, the feeding tank from which the siphon projects will have a capacity relatively to the tank E¹ that the water of the feeding tank will be sufficient when siphoned into the tank E from the 80 feeding tank to give ample operating weight to the tank E¹ and to attain a predetermined level to raise the float L high enough to give the proper normal distance between the contact bridge L¹ and the mercury cups 85 L². In the event that more water will flow into the tank E¹ through the siphon from the feeding tank above than is actually required, it will overflow through the pipe F and eventually pass out through the outlet pipe 90 F³. However, the upper feeding tank from which the siphon leads will be controlled as to the amount of water flowing thereinto by the float and arm connected with the feed valve of the main pipe M in a manner similar to the ordinary flushing tank. As shown by Fig. 2, the wires forming the circuit A² engage sheaves arranged as shown or disposed otherwise within the interior of a building, apartment or room, 100 these wires being connected to a circuit closing means C³ shown diagrammatically by Fig. 2 and in detail by Figs. 3 and 4 and consisting of an adjustable mercury cup Q under the point of an adjustable weighted bobbin P² capable of sliding on arm P of a bell-crank lever and also adjustable for the other end of same wire A², at a slot in arm P¹. The wire A² has its slack taken up by winding the bobbin P² in accordance with 110 the adjustment of said bobbin lengthwise of the arm P of the bell-crank lever, and in addition slack in the said wire may be taken up by shifting the same from one slot to another slot of the arm P¹, and by this means 115 the said wire A² may be maintained relatively taut. In the event of a fire breaking out in a room or apartment in which this part of the apparatus is operatively associated the part of the wire A² within the room or apartment that may be affected by extreme heat and slackened will cause a corresponding slackness relatively to a primal adjusted taut condition of the portion of the wire engaging the bobbin, and the bell-crank lever which has been held in the normal position shown by Fig. 4 will be permitted to swing so that a contact may be 120 made between the contact point of the bobbin P² and the mercury cups, thereby closing 125 130

the circuit and operating the alarm signal. The bell crank is most sensitive when bobbin P^2 is on the outer slot of the arm P and the wire is engaged in the lowest slot of arm P^1 , 5 and vice-versa. The bobbin P^2 can wind in any slack and be fixed by a top thumbscrew, and the cup Q can be moved and fixed under it as shown, the whole being on an insulated board. The modification just 10 closed and as shown by Figs. 2, 3 and 4 will be connected up to the apparatus shown by Fig. 1 in place of the alarm box B^4 through the medium of the wires A^1 and the location of the fire in the building, room or 15 apartment will be disclosed by the operation of the signaling means and annunciator embodied in the apparatus shown by Fig. 1 and as hereinbefore described.

Having described my invention, what I 20 desire to protect by Letters Patent of the United States, is:—

1. In an alarm, the combination of an electrically-controlled shutter; a circuit closer operatively associated therewith; a 25 circuit wherein said circuit closer is included; an electromagnet included in said circuit; a vertically movable weighted element having means for automatically restoring it to normal position; trip mechanism controlled by said magnet for normally holding said element in raised position; a signal; and connections between said 30 element and said signal for automatically actuating the latter when the former descends consequent upon being tripped.

2. In an alarm, the combination of an electrically-controlled shutter; a circuit closer operatively associated therewith; a circuit wherein said circuit closer is included; an electromagnet included in said 40 circuit; a weighted element; trip mechanism controlled by said magnet for normally holding said element in raised position; a signal; connections between said element and said 45 signal for automatically actuating the latter when the former descends consequent upon being tripped; and means for automatically resetting said shutter during such descent.

3. In an alarm, the combination of an 50 electrically-controlled shutter; a circuit closer operatively associated therewith; a circuit wherein said circuit closer is included; an electromagnet included in said circuit; a water tank; means controlled by

said magnet for normally holding said tank 55 in raised position, said tank having means for discharging its contents during its descent consequent upon release; a signal; and connections between said tank and said signal for automatically actuating the latter 60 when the former descends.

4. In an alarm, the combination of an electrically-controlled shutter; a circuit closer operatively associated therewith; a circuit wherein said circuit closer is included; 65 an electromagnet included in said circuit; a water tank; means controlled by said magnet for normally holding said tank in raised position, said tank having means for discharging its contents during its descent consequent upon release; a signal; 70 connections between said tank and said signal for automatically actuating the latter when the former descends; and means for automatically refilling said tank during its 75 ascent.

5. In an alarm, the combination of an electrically-controlled shutter; a circuit closer operatively associated therewith; a circuit wherein said circuit closer is included; 80 an electromagnet included in said circuit; a weighted element; trip mechanism controlled by said magnet for normally holding said element in raised position; a signal; connections between said element 85 and said signal for automatically actuating the latter and resetting said shutter to break said circuit when the said element descends consequent upon being tripped; auxiliary means for closing said circuit at the completion 90 of such descent to reset said trip mechanism and raise said element.

6. In an alarm, the combination of an electrically-controlled circuit closer; a circuit wherein said circuit closer is included 95 and also embodying signal operating means; a signal connected to said signal operating means; and means operable automatically consequent upon the closing of said circuit for actuating said signal and provided with 100 devices for automatically resetting the same in normal condition.

In testimony whereof, I affix my signature, in presence of two witnesses.

HENRY SYMES.
